FIG. 4

FIG. 1.

FIG. 2

INVENTOR:
SYDNEY MARQUIS

BY George W. Saywell
ATTORNEY

UNITED STATES PATENT OFFICE

SYDNEY MARQUIS, OF CLEVELAND, OHIO, ASSIGNOR TO THE ROSS MANUFACTURING COMPANY, OF CLEVELAND, OHIO, A CORPORATION OF OHIO

WHEEL DRESSER

Application filed January 10, 1929. Serial No. 331,587.

My invention particularly relates to a wheel dresser assembly comprised of a plurality of series of disks of different sizes. In the accompanying drawings and the descriptive detail hereinafter given I show and describe two series of such disks arranged in alternate relation. The purpose of the invention is to provide a disk construction and assembly that will present dressing teeth capable of effecting a picking action even after considerable service and at a time when the teeth would presumably be worn down so as to present flat surfaces. This is effected by bringing the unimpaired teeth of the smaller disks into play after the teeth of the larger disks have been worn down. The improved assembly is adaptable for use as a dressing tool as well as for use as a picking machine.

The annexed drawings and the following description set forth in detail certain means embodying my invention, such disclosed means, constituting, however, but one of the various forms in which the principle of the invention may be illustrated.

In said annexed drawings:

Figure 1 is a side elevation of my improved dressing wheel assembly rotatably mounted in a bracket adapted to be fixed to a reciprocating slide for feeding the dresser across the grinding face of an abrasive wheel, to effect a dressing action in a manner well known to those skilled in the art;

Figure 2 is a front elevation of the elements shown in Figure 1, the view being partly in vertical section through the axis of the dresser assembly to show the method of mounting; and

Figures 3 and 4 are detached views of one of each of the two series of different size disks comprising my improved assembly.

Referring to the annexed drawings in which the same parts are indicated by the same respective numbers in the various views, comparatively large and small toothed disks are indicated by the numbers 1 and 2, respectively, which are of annular construction and provided with internal serrations 3 adapted to register between complementary knurls 5 formed upon a rotatable hub

member 4 whereby the two series of disks 1 and 2 may be formed into the complete rotatable dresser assembly. The body and teeth 6 of the disks 1 of one series of disks are of larger diametrical dimension than the body and teeth 7 of the disks 2 of the other series. These disks 1 and 2 are secured to the hub member 4 in alternate relation, being also relatively staggered, in the form herein shown, as plainly seen in Figures 1 and 2, and the dresser assembly thus formed is mounted upon a spindle bolt 9 secured in a bracket 10 adapted to be fixed to a reciprocating slide 11 by means of which the dressing wheel assembly may be fed across the grinding face of an abrasive wheel to dress the latter.

During the dressing operation a picking action by pointed teeth is desirable and in the standard construction of dresser assemblies such picking action is obtainable only while the points of the teeth are comparatively sharp. Consequently, so soon as the points are worn down to present a flat surface to the grinding wheel face this desirable picking action is eliminated. However, by my improved assembly, the points of the teeth 7 of the smaller disks 2 take up and continue the desirable picking action at a time when the ends of the teeth 6 of the larger disks 1 are worn down so as to present a surface so flat as not to furnish this picking action.

My invention is not limited to two series of disks of different sizes but any reasonable number of series of disks is within the spirit of the invention. Furthermore, it is not necessary that the series be uniformly rotated or that the disks be arranged in absolutely normal staggered relation but only such an arrangement as will furnish a picking action by scattered and separated disk teeth during the entire life or action of the assembly.

What I claim is:

1. A wheel dresser comprising an assembly of a plurality of series of toothed disks, each series consisting of a plurality of dressing disks of the same diameter, the series being distinguished one from the other in con-

sisting of disks of different diameters, and disks of different diameters being intermingled so that disks of small diameter lie between disks of relatively larger diameter
5 whereby a continuous effective picking action may be had until the teeth of the smallest disks have been worn down.

- 10 2. A wheel dresser comprising an assembly of two series of toothed disks, each series consisting of a plurality of dressing disks of the same diameter, the series being distinguished one from the other in consisting of disks of different diameters, and disks of different diameters being intermingled so that disks of small diameter lie between disks of relatively larger diameter whereby a continuous effective picking action may be had until the teeth of the smaller disks have been worn down.
- 15 20 3. A wheel dresser comprising an assembly of two series of toothed disks, each series consisting of a plurality of dressing disks of the same diameter, the series being distinguished one from the other in consisting of disks of different diameters, and disks of different diameters being arranged in alternate relation so as to furnish a continuous effective picking action until the teeth of the smaller disks have been worn down.
- 25 30 Signed by me this 21st day of Dec., 1928.
SYDNEY MARQUIS.
